UNITED STATES PATENT OFFICE

ROBERT FEIN, OF NEW YORK, N. Y.

DESIGN FOR A SIGNAL LIGHT FOR VEHICLES

Application filed June 20, 1932. Serial No. 44,139. Term of patent 7 years.

To all whom it may concern:

Be it known that I, ROBERT FEIN, a citizen of the United States, residing at New York, in the county of Kings and State of New York, have invented a new, original, and ornamental Design for a Signal Light for Vehicles, of which the following is a specification, reference being had to the accompanying drawing, in which;

Fig. 1 is a face view of a signal light for vehicles showing my new design.

Fig. 2 is a top plan view of the same.

Fig. 3 is a perspective view of the same.

I claim:

The ornamental design for a signal light for vehicles, as shown.

In testimony whereof I have affixed my signature.

ROBERT FEIN.
